METHOD AND APPARATUS FOR GRINDING
BALL SEATS IN STEEL ARTICLES

Ottis R. Briney, Jr., Pontiac, Mich.

Application May 21, 1942, Serial No. 443,868

2 Claims. (Cl. 51—71)

This invention relates to an improved method of grinding or honing ball seats in metal articles and further to the apparatus employed in the practice of such method.

One of the objects of the invention is to grind a spherical recess in a machine part by placing a dry, abrasive laden ball therein, then moving the ball under pressure over the surface of the recess in an ever changing path.

Another object of the invention is to provide a ball which is formed from a material of a character capable of supporting an abrasive yet capable of repeated use without appreciable loss of size and form. Exemplary of such material is a high carbon chrome alloy steel carburized but not quenched or a steel ball of a similar alloy which is hardened and ground, then spheroidized or annealed.

Another object of the invention is to charge or load the surface of a honing ball with an abrasive by either violently tumbling a metal sphere in a receptacle containing an abrasive flour or diamond powder or rolling a ball, under pressure between flat horizontal steel plates having a coating of a dry abrasive flour thereon.

A further object of the invention is to provide a platen for supporting and effecting the movement of the balls relative to the work during the honing operation. To this end the invention contemplates a pad formed from a material which offers a higher frictional surface resistance than that of the work, a material which possesses sufficient resiliency to compensate for such irregularities in height as may occur in mounting a number of work pieces in the holder and a material which is capable of being impregnated with the abrasive worn from the balls as they are agitated in the work. A sheet of bonded comminuted cork has been found, in practice, to provide such of the foregoing prerequisites as are essential to the successful exercise of the improved honing method. Rubber or hard felt pads may also be used if desired.

Other objects and advantages more or less ancillary to the foregoing and the manner in which all the various objects are realized will appear in the following description, which considered in connection with the accompanying drawing, sets forth the preferred embodiment of the invention.

In the drawing which shows, for illustrative purpose only, one of the forms of apparatus that may be used in carrying out the method:

Fig. 1 is an elevational view of a fragmentary

portion of a drill press showing the work holder mounted thereon;

Fig. 2 is a plan view of the work holder illustrated in Fig. 1;

Fig. 3 is a vertical sectional view through a portion of the work holder, the section being taken on a plane indicated by the line 3—3 in Fig. 2;

Fig. 4 is a sectional view through a work piece 10 which is typical of the type of product that can be finished by the improved method;

Fig. 5 is an elevational view, shown partially in section, of the tumbling machine used in charging the honing balls; and

Fig. 6 is an elevational view of an alternate form of mechanism used in charging the honing balls.

Referring first to Fig. 4, the work piece chosen for the purpose of illustration comprises a carburized semi-finished steel body 10, machined with a reamed ball seat 11 therein. End cutting tools, such as rose reamers, despite the speeds and feeds employed in the use thereof are apt to score the work and leave concentric grooves and ribs which obviously are subject to abnormal wear. Moreover, the contour of a recess is seldom spherical due to deformation of the work in hardening and the tendency of the tool or work to "run" during machining operations.

As contemplated herein such irregularities in a ball seat are abraded therefrom by rolling a honing element in an ever changing path over the surface of the ball seat and in addition by simultaneously moving the work in such a manner as to cause the ball to spin or twist within the recess.

In production the method of abrading the ball seats is carried out by loading a plurality of work pieces 10 in a holder or chuck 12; placing a honing or grinding ball 13 in each recess, engaging the balls with a surface such as the cork pad 14 illustrated in Figs. 1 and 3, then moving the chuck relative to the pad under sufficient pressure to effect a rotative movement of the balls. The chuck preferably comprises a metal disc drilled or recessed to support the work with the ball seat portions thereof protruding from the face of the chuck in equidistant relation to each other.

In contradistinction to a lapping operation which comprehends the use of a fluidic mixture of oil and emery and a porous or ductile lapping tool, the present invention contemplates a dry grinding process effected through the medium

of a cutting tool formed from a close grained metal sphere having a finely divided abrasive embodied in the surface thereof. Such grinding or honing balls may be formed of steel balls of the type commercially used in the manufacture of anti-friction bearings, though it is to be understood that other metals may be used with equal facility. The honing balls are prepared by pounding or rolling a finely milled abrasive flour or diamond dust into the surface thereof. The pounding operation is preferably effectuated by a tumbling machine comprising generally a rotatively driven shaft 15 (Fig. 5) having a spider keyed thereon which supports a plurality of cups 16 provided with removable caps or cover plates 17. The cups 16 are partially filled with the balls 13 and the abrasive, sufficient space being left therein to permit the charge to fall against the end walls and sides of the cup during rotation and thus produce a violent pounding and rubbing action between the balls and abrasive.

An alternate method of charging the balls may be effected by covering a flat steel plate such as shown in Fig. 6 with an abrasive flour, placing one or more balls thereon, then rotating under pressure a second steel plate thereover.

After the chuck 12 is loaded with the work pieces and a honing ball is placed in each recess therein the chuck is inverted and placed upon the pad 14 with the balls engaged therewith. As shown in Fig. 1, the pad is mounted upon the table 18 of a drill press, the spindle 19 thereof being provided with a crank arm 20 having a pin 21 therein adapted for engagement within a recess 22 formed in the center of the chuck 12. It will be understood that the drill press shown herein is used merely in an illustrative sense and that numerous other machines or mechanism may be employed to drive the chuck or pad without departing from the scope or spirit of the invention. The circumferential edge of the chuck is drilled for the reception of a rod 24 which is designed to engage the column 25 of the machine and effect the oscillation of the chuck during its orbital movement over the pad 14. The rod is preferably constructed for detachable connection with the chuck in order to accommodate the removal thereof during loading. If desired the free end of the rod may be provided with a contractile spring 26 mounted to maintain the rod in intimate relation with the column 25.

During the operation of the machine rotation of the balls within their seats is effected by

movement of the chuck by the traction offered by the pad and by the weight and driving forces imposed upon the balls. In addition to the rotative movement of the balls the path or direction of translation and the rotative speed thereof will change as the chuck is oscillated about its axis while moving in the path described by the movement of the pin 21. The tortuous paths described by the work pieces will bring the balls therein into contact with the entire surface of the respective recesses and will, moreover, cause each ball to roll in directions transaxial to such concentric grooves and ribs as may have been formed by the reamer or cutting tool during the initial machining operation of the ball seats.

In practice it has been found that by pressure rolling or pounding a fine abrasive flour into the surface of a steel ball a dry honing element can be produced which may be used over and over again before it has to be discarded for loss of size or form.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. Mechanism for polishing ball seats in metal work pieces comprising, a stationary table, a pad thereon, a holder for a plurality of work pieces, abrasive laden balls in the ball seats in the work pieces in said holder, engaged with said pad and constituting the support for the holder, a rotatively driven crank pivotally connected with said holder, a stop adjacent said table and a rod on said holder yieldably engaged with said stop for oscillating said holder about its pivotal connection with said crank.
2. Mechanism for polishing a ball seat in a metal work piece comprising, a stationary table, a work piece holder superjacent thereto, an abrasive laden ball intermediate the table and the ball seat in a work piece in said holder, a rotatively driven crank loosely connected with said holder and means for moving said holder in a substantially oval path.
